UNITED STATES PATENT OFFICE.

WILLIAM R. ELLIS, OF CHICAGO, ILLINOIS, ASSIGNOR OF ONE-HALF TO
JAMES L. MALLORY, OF SAME PLACE.

CAR-DOOR.

SPECIFICATION forming part of Letters Patent No. 610,940, dated September 20, 1898.

Application filed September 2, 1897. Serial No. 650,325. (No model.)

To all whom it may concern:

Be it known that I, WILLIAM R. ELLIS, a citizen of the United States, residing at Chicago, in the county of Cook and State of Illinois, 5 have invented a certain new and useful Improvement in Car-Doors, which is fully set forth in the following specification, reference being had to the accompanying drawings, in which—

10 Figure 1 is a side elevation of the upper portion of a car and car-door constructed according to my invention. Fig. 2 is a vertical cross-section on the line 2 2 of Fig. 1. Fig. 15 3 is a vertical cross-section on the line 3 3 of Fig. 1. Fig. 4 is a horizontal section on the line 4 4 of Fig. 2.

My invention relates to car-doors such as are used upon freight-cars, and has for its object to provide a construction which shall render such doors less liable to displacement on the one hand and to binding or other impediment on the other hand in their movement back and forth across the door-aperture.

20 My invention further relates to such a construction for car-doors as shall provide an extremely simple and easily-manufactured form of hangers and track and which shall be so constructed and arranged that the track shall coöperate with bearing-surfaces on the hanger 25 to keep the door in place and at the same time furnish a complete protection for the upper part of the door against rain, snow, cinders, and dirt generally.

Referring to the drawings by letter, A represents the side of the freight-car, provided with an aperture or doorway B. Above the said aperture, upon the outside of the car, I mount a horizontal track C, comprising an upward vertical flange C', adapted to be secured by the screws c to the side of the car, a horizontal web C², provided with a raised track c' on its upper surface, and a downward vertical flange C³ at the opposite side of the web C² and the flange C'.

40 The door D may be of any preferred construction. Upon the outside of the said door, near each of its upper corners, is mounted a hanger E. The said hanger comprises a lower plate portion E', adapted to be secured to the body of the door, an outwardly-extending bracket E², and an upwardly-extending arm

E³, which is integral with the outer side of the said bracket. The bracket E² is provided with an inner and an outer guide-surface e and e', respectively, forming between them a flaring guideway e², adapted to receive the lower edge of the downward flange C³, which forms part of the track C aforesaid. In the upper extremity of the arm E³ is mounted a supporting-roller E⁴, adapted to roll upon the track proper, c', and thus to support the door and permit of its movement.

Midway between the two hangers I secure upon the upper edge of the door D a casting F, comprising a downward strap F', adapted to be secured to the body of the door, a lower horizontal plate F², a vertical web F³ on the inner end thereof, and an upper horizontal plate F⁴, all preferably made integral with the strap F' in a single casting. In the two 70 horizontal plates F² and F⁴ and adapted to revolve freely between them is mounted upon a vertical pivot a roller F⁵, the periphery of which projects outward beyond the strap F', as particularly illustrated in Fig. 3.

75 From the construction hereinabove described and illustrated in the drawings it will be obvious, in the first place, that the car-door is securely held upon its track and the guide-surfaces e and e' prevent the lower end of the door from being swung out to any considerable extent and entirely obviate displacement of the door as a whole. At the same time the said surfaces are so curved as to prevent binding of the same with the track-flange in the ordinary movement of the door.

It will be further seen that the roller F⁵ prevents any of the intermediate parts of the door between the two hangers coming in contact with the track-flange by any warping of the door, such as very commonly takes place. In case the middle of the door warps outward the roller F⁵ bears against the flange C³ and the movement of the door is not impeded. Thus the flange C³, having under no circumstances any bearing against the door, except at the curved guide-surfaces e and e', and the roller F⁵, has no opportunity to bind and prevent easy movement of the door back and forth. At the same time, as before stated, 100 the said flange in coöperation with the guide-surfaces prevents the swinging outward of

the lower edge of the door and holds the supporting-roller E⁴ in proper position upon its raised track c'. Furthermore, it will be readily seen that the construction I employ, in which 5 the track extends completely over the top of the door and the flange C³ projects downward on its outer side and below the top, completely covers the top of the door in all positions, whether open or closed, and absolutely 10 prevents snow or rain from getting at the top of the door to cause it to swell or decay, and prevents the accumulation of any dirt thereon so as to interfere with the working of it. It thus results that the flange C³ has 15 a double function of serving as a bearing to keep the door in a proper position and to protect the top of the said door—a valuable improvement, which is, so far as I am aware, original with me.

20 It will be apparent that some changes may be made in the details of the construction shown without departing from the principle of my invention. Thus two or more rollers F⁵ may be employed instead of the one 25 shown, &c.

What I claim, therefore, and desire to secure by Letters Patent, is—

1. In a car, the door D; the hangers E adapted to be secured to the upper portion of 30 the outer side of the door, and provided with guide-surfaces, and with an arm E³ carrying a contact-surface for supporting the weight of the door; and a track C, in section consisting of a single piece, secured to the car, 35 extending completely over the door, and provided with a downwardly-extending flange in proximity to the guide-surfaces and below the top of the door, said track serving as a support for the contact-surface and as a protecting-covering for the top of the door, substantially as described.

2. In a car, the door D; the hangers E adapted to be secured to the upper portion of the outer side of the door, and with an arm 45 E³ carrying a contact-surface for supporting the weight of the door, said contact-surface being substantially over the center of the door; and a track C, substantially Z-shaped in section, secured to the car by one flange, 50 and having the connecting-web extending completely over the door and serving as a support for the aforesaid contact-surface, and having the other flange extending downwardly below the surface of the top of the door, substantially as and for the purposes described.

3. In a car, the door D; the hangers E adapted to be secured to the upper portion of the outer side of the door, and provided 60 with guide-surfaces, and with an arm E³ car-

rying the roller E⁴ for supporting the weight of the door; and the track C, in section consisting of a single piece and substantially Z-shaped, secured to the car, its central web extending completely over the door, and serving as a track for the roller E⁴, and one of its flanges extending downward in proximity to the guide-surfaces and below the top of the door, substantially as and for the purposes described.

4. In a car, the door D; the hangers E adapted to be secured to the upper portion of the outer side of the door, and provided with arms E³ carrying a contact-surface for supporting the weight of the door; and track 75 C secured to the car and having a central web extending completely over the door and forming a support for the aforesaid contact-surface, and provided with a flange C³ extending downwardly below the top of the 80 door on the outer side thereof; and one or more rollers F⁵ mounted on the upper edge of the door and adapted to bear against the inside of the flange C³, substantially as and for the purpose described.

5. In a car, the door D; the hangers E adapted to be secured to the upper portion of the outer side of the door, and provided with the guide-surfaces e and e', the surface e being convex, and with an arm E³ carrying 90 a contact-surface for supporting the weight of the door; and a track C, in section consisting of a single piece, secured to the car, its central web C² extending completely over the door and serving as a support for the contact-surface, and provided with a flange C³ extending downwardly between the guide-surfaces e and e' and below the top of the door, substantially as and for the purposes described.

6. In a car, the door D; the hangers E adapted to be secured to the upper portion of the door, and provided with guide-surfaces, and with an arm E³ carrying the roller E⁴ for supporting the weight of the door; a track C 105 substantially Z-shaped in cross-section secured to the door, with its central web extending completely over the door and serving as the support for the rollers E⁴, and having a flange C³ extending downward in proximity to the guide-surfaces and below the top of the door; and one or more rollers F⁵ mounted upon the upper edge of the door adapted to bear against the inside of the flange C³, substantially as and for the purpose described.

WILLIAM R. ELLIS.
